S. L. SIMON

BASEBALL BAT

Filed March 20, 1923

Inventor

S.L. Simon

By *Alfred J. Randolph, Jr.* Attorney

UNITED STATES PATENT OFFICE.

SAMMIE L. SIMON, OF FRANKLIN, INDIANA.

BASEBALL BAT.

Application filed March 20, 1923. Serial No. 626,338.

To all whom it may concern:

Be it known that I, SAMMIE L. SIMON, a citizen of the United States, residing at Franklin, in the county of Johnson and State of Indiana, have invented certain new and useful Improvements in Baseball Bats; and I do hereby declare the following to be a full, clear, and exact description of the invention, such as will enable others skilled in the art to which it appertains to make and use the same.

In playing the game of baseball, many foul hits result, the same being attributed largely to the slipping of the ball when coming in contact with the bat, and it is the purpose of the present invention to provide a bat which will eliminate foul hits or reduce the same to a comparatively small number, and with this object in view, the invention consists of a bat provided with concavities or indentations in close relation, the depressions conforming to the surface of the ball and their outer edges being rounded to prevent possible injury to the ball when coming in contact therewith.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a side view of a baseball bat embodying the invention.

Figure 2 is an enlarged longitudinal section on the line 2—2 of Figure 1, and

Figure 3 is a similar view on the line 3—3 of Figure 1.

Corresponding and like parts are referred

to in the following description and designated in the several views of the drawings by like reference characters.

The numeral 1 designates the body of the bat which may be of any usual construction. In accordance with the present invention, the striking portion of the bat is provided in its outer side with concavities, indentations or recesses 2 in close relation, and these indentations conform approximately to the diameter of the ball and their outer edges are made rounding to prevent injury to the ball when coming in contact therewith. The indentations 2 are disposed in close relation and are arranged in lines longitudinally, circumferentially and spirally of the bat, thereby insuring the ball coming in contact with some one of the depressions and preventing a foul hit and this arrangement of the indentations also prevents any weakening of the hitting surface of the bat.

What is claimed is:

1. A bat having a plurality of closely related sockets in its hitting surface, said sockets being independent of each other and each socket having an endless side wall.

2. A baseball bat having a plurality of closely related sockets in its hitting surface, said sockets being independent of each other, and each socket having an annular side wall.

3. A baseball bat having a plurality of closely related sockets in its hitting surface, said sockets being independent of each other, and each socket having an annular side wall, the outer edges of said wall being rounded, and said sockets being arranged in lines extending longitudinally, circumferentially and spirally.

In testimony whereof I affix my signature in presence of two witnesses.

Sammie L. Simon.

Witnesses:

James M. Robinson,
Margery E. Lane.
